(57) **CLAIM**

The ornamental design for an upright element for a net frame, as shown and described.

DESCRIPTION

FIG. 1 is a front elevation view of an embodiment of an upright element for a net frame according to our new design; FIG. 2 is a rear elevation view thereof;

FIG. 3 is a left side elevation view thereof;

FIG. 4 is a right side elevation view thereof;

FIG. 5 is a top plan view thereof; and,

FIG. 6 is a bottom plan view thereof.

The broken lines immediately adjacent shaded areas represent the bounds of the claimed design while all other broken lines are directed to environment and are for illustrative purposes only; the broken lines form no part of the claimed design.
